[57] CLAIM

The ornamental design for a recycle container with removable bins and the like, as shown and described.

DESCRIPTION

FIG. 1 is a perspective view of a recycle container with removable bins and the like showing our new design; with cover in open position;

FIG. 2 is a top plan view thereof;

FIG. 3 is a left side elevation thereof; with cover in closed position; the right side elevation being a mirror image thereof; and

FIG. 4 is a rear elevation thereof; with cover in closed position.

The bottom is plain and unornamented.

FIG. 1

FIG. 2

FIG. 3

FIG. 4
